UNITED STATES PATENT OFFICE.

WALTER S. ROTHERHAM, OF POMPTON LAKES, NEW JERSEY, ASSIGNOR TO E. L DU PONT DE NEMOURS & COMPANY, OF WILMINGTON, DELAWARE, A CORPORATION OF DELAWARE.

DRAWING PRESS.

Application filed January 19, 1921. Serial No. 438,400.

To all whom it may concern:

Be it known that I, WALTER S. ROTHERHAM, a citizen of the United States, and a resident of Pompton Lakes, in the county of Passaic and State of New Jersey, have invented a certain new and useful Drawing Press, of which the following is a specification.

This invention relates to presses for drawing metal articles by forcing the same through dies to work the articles into desired form. More particularly, the invention relates to a press for drawing cylindrical shells, increasing their lengths at the expense of their diameters. Since the illustrated press has been found particularly useful in the drawing of copper shells for blasting caps, I describe it with more particular reference to that art, but it will be understood that I do not restrict it thereto.

Blasting caps are used to detonate high explosive charges. A shell about two inches long and one quarter inch in diameter, as drawn by the present press from a cup about three-eights inch long by one-half inch in diameter, the shell as produced by the press having a closed bottom and open top, is loaded with a sensitive and violent explosive, for example, fulminate of mercury, and a fuse is inserted in the open end of the loaded shell, or cap, and the cap is placed in close relation to the charge of high explosive. The explosion of the cap gives the shock and heat necessary to cause detonation of the charge.

With the shells destined for uses such as outlined, they must, to meet competition, be produced in large quantities, at relatively low cost, and of uniform dimensions. The present press provides for such production.

One object of the invention is to provide a drawing press having a series of dies of diminishing diameters in each of which each cup is drawn in succession to produce a shell, and having positively and accurately controlled means for shifting each of the cups step-by-step from one die to the next along the series.

Another object is to provide a drawing press having a cup-shifting means, and means for feeding the cups to the dies in substantial correspondence with the shifting means.

Another object is to provide a drawing press in which shells of comparatively great length can be completely drawn, from the cup to the fully drawn shell, in a continuous operation uninterrupted by annealing between the draws. 55

Another object is to provide an article shifting mechanism for drawing presses. 60

Another object is to provide an article feeding mechanism for drawing presses.

To these ends, and also to improve generally upon devices of the character indicated, my invention consists in the various matters hereinafter described and claimed. 65

Without restricting my invention thereto I describe it by reference to the drawing press illustrated in the accompanying drawings. The various figures of the drawings except Figure 1, have more particular relation to the right hand half of the machine as illustrated in Figure 1; in the figures relating to the drawing portions of the press 70 the parts are shown substantially as they appear when the shell-shifting slide is at the limit of its forward travel, the dwell is occurring and drawing substantially taking place, except that in Figures 1 and 2 75 the plunger holder has been raised without disturbing the other parts, so as to the better show the plungers. In the drawings:—

Figure 1 is a front view of the press, somewhat elementary in character and with 80 various details omitted;

Figure 2 is an end view looking in the direction of the arrow 2, Figure 1;

Figure 3 is a plan view looking in the direction of the arrow 3, Figure 1; 85

Figure 4 is a longitudinal sectional view substantially on line 4—4 of Figure 3;

Figure 5 is a cross-sectional view substantially on the line 5—5 of Figure 3;

Figure 6, is a bottom plan view of one of 90 the cam slides, the lower or front one as illustrated in Figure 3;

Figure 7 is, substantially, a graphical representation of the relative movements of the major parts of the drawing parts of the 95 machine;

Figure 8 is a face view of the feeding disc and related parts, seen in the direction of the arrow 8, Figure 1;

Figure 9 is substantially a diametrical 100 section on the line 9—9 of Figure 8;

Figure 10 is an edge view of the parts related to the feeding disc looking in the direction of the arrow 10, Figure 8, and

Figure 11 is an enlarged fragmental section view through the feed disc substantially on line 11—11 of Figure 8, looking radially outward from the centre of the disc, and showing the carrier in normal, untripped, position.

10 The illustrated press comprises two press units, A and B, fed from a common hopper H by the feeding mechanisms designated generally as A^H and B^H. Since the units A and B are alike, i. e. rights and lefts, and 15 their mechanisms A^H and B^H alike, I shall describe more particularly the unit A and its mechanism A^H, the description sufficing for the unit B and its mechanism B^H; and, first, I shall describe those portions of the 20 unit A which act upon the cups to draw them and to shift them, and, next shall describe the feeding mechanism A^H for feeding the cups from the hopper to the drawing and shifting parts of the unit A.

25 The frame 1 carries a series of dies or matrices 2 into each of which in turn a specified cup is introduced and is partially drawn. The dies are of decreasing diameters in the direction of travel of the cups 30 from left to right (Fig. 4) and are sufficient in number to provide for the complete drawing of the cups into shells with the amount of drawing at each die sufficiently small to insure that the partially drawn shells will 35 not have to be annealed between one draw and the next, the present machine having six dies. A series of plungers 3 is carried by the reciprocating plunger holder 4, for entering the dies to force the shells into the 40 dies and draw them. The cups to be drawn are fed from the pipe 5 at the left, open end up and one at a time, and lie on the rest there-below until transported to the dies.

45 For forcing the partially drawn shells upward out of the dies, after they have been forced into the same by the plungers 3, there is provided a series of ejectors 6 (Fig. 4), one for each die except the last, 2¹. These ejectors, or pins, 6 are urged to lowered position by springs 7 expanding between abutments 8 and 9 on the machine frame and pins respectively, but are raised by the cams 10, in proper timed relation to the rising of the plungers. The cams are carried on the rotating shaft 11 (Figs. 2 and 4) and are operatively associated with the pins 6 by the levers 12 oscillatably mounted on the machine frame at 12^a and each having a nose 13 disposed between its co-related cam 10 and ejector 6. The partially drawn shells, as they, followed by the ejectors 6, rise from the dies 2, rest above the dies, there being provided stripper plates 14 (Fig. 4) carried by a block 15 on the bed 16 and each 50 provided with an aperture 17 through which

the related plunger reciprocates bringing the shell in contact with the lower side of the plate to strip the shell from the plunger; similarly with the scrap, which rises with the last of the plungers. The shells, after 50 being transported (as cups) from below the pipe 5 to the first die 2¹, and shifted from die to die, by the mechanism to be described next below, are passed through the last die, 2¹, at the right and discharged through the 55 outlet 18, the relative dimensions of the last die and its plunger providing for the shell not being carried upward with the plunger on its retreat. The scrap, or small ring of metal trimmed from the top of the shell at 60 the last die by the cooperating shoulders 3¹ (Fig. 1) and 2^s (Fig. 4) on the last plunger and die, is moved to the air box or outlet 19, by the just mentioned mechanism, and blown through the passage 20, by an air blast from 65 the pipe 21.

The mechanism for shifting the cups from below the pipe 5 to the first die 2¹, shifting the partially drawn shells step-by-step from die to die, and shifting the scrap 90 from the last die, 2¹, to the air box 19 comprises, in general (Figs. 3, 4 and 5): a main or carrying slide, designated generally as 22, for moving the articles, and reciprocated by the cam 23 on the shaft 24; a series of coupling devices, each shown by way of example as comprising a pair of coupling units or fingers 25, for coupling the articles to the main slide to be drawn along thereby; means, shown as springs 26, for forcing 95 the couplings into coupling position; and means, here exemplified by cam slides 27, for controlling and determining the position—coupled or uncoupled—of the couplings 25, such last-named means being operated by the cams 28—29 on the shaft 24. The coupling devices are mounted on and carried by the main slide; the relative positions of the main slide and the cam slides 100 determine the positions of the coupling devices. In operation, the couplings connect the cup to be drawn, the partially drawn shells, and the scrap, to the main slide; the main slide moves forward to bring the cup to the first die, each partially drawn shell 110 to a (smaller) die other than that in which it has just been drawn, and the scrap to the outlet; the couplings uncouple the articles in their new positions and drawing occurs; and the main slide goes back to original position, 115 ready to repeat the cycle; and so on. As to the more important features of this mechanism:—

The carrying slide or shifter 22 is, for convenience, composed of two sections 22^a and 22^b connected by the screw 30 which passes through a bridge piece 31, attached to the sections 22^a at 32, and is screwed into the tongue 33 on the section 22^b and inserted in the socket 34 in the section 22^a. The por-

tion 22^a carries rollers 35 and 36 for cooperation with the cam 23 which reciprocates the slide 22, the portion 22^a being slotted at 37 to permit reciprocation with respect to 5 the shaft 24 which passes through the slot 37.

The portion 22^b, which carries the couplings 25 and immediately moves the articles, is provided, at each side of a central slot 38, for exposing the dies and permitting 10 the passage of the plungers 3, with a series of coupling-receiving recesses 39. The number of these recesses is sufficient to provide for a pair of couplings one in excess of the number of dies—in the present 15 case seven pairs. These recesses 39 are oppositely disposed, to provide for the units of a coupling pair being arranged oppositely, and are spaced longitudinally of the slide, each from next, in correspondence 20 with the spacing of the location or position below the feed pipe 5, the dies, and the exit 20 into the air box 19; the parts in the present instance are substantially equidistant. In the bottom of each recess 39 25 is an opening 40 of substantially the contour shown.

A coupling unit 25 is received in each recess 39 for reciprocation backward and forward therein, the units being covered 30 by plates 22^x attached to the portion 22^b. Each unit is urged or moved toward the dies 2 by its co-related expanding spring 26 located between the back end of the coupling unit and a wall 41 on the portion 35 22^b. The units are recessed at 25^a in their forward ends to substantially correspond to one-half of the periphery of the article. The previously referred to unit-controlling cam slides 27, one for each longitudinal series 40 of coupling units, are carried in longitudinal slide-ways 42 located in the bottom of the portion 22^b and extending into the portion 22^a. Each unit 25 carries on its under side a cam roller 43 located in the previously 45 referred to opening 40. The cam slide 27 (Fig. 6) for cooperation with the units of a specified series lies between the rollers 43 of that series and the dies 2. It has on its roller-facing side a series of cam surfaces 44, each such surface comprising a deep-cut portion 44^a and a shallow cut portion 44^b. Evidently, as the slides reciprocate, when the surfaces 44^a are in contact with the rollers 43 the coupling units will 55 be retracted into uncoupled position; and when the surfaces 44^a are in contact with the rollers 43, permitting the springs to push the units into forward position, the ends 25^a of the units substantially encircle 60 the articles and couple them to the main slide to be drawn along thereby. The cam slides are mated to cause all the various units to advance and retreat together. The position of the cam slides 27, and hence the 65 position of the couplings, depends upon the

relative position of the cam slides and the main slide 22 as they are reciprocated. As previously mentioned, the cam slides are reciprocated by the cams 28—29.

The connection between the cam slides 70 and the cams 28—29 is as follows (Figs. 2, 3 and 4):—The slides extend into the portion 22^a of the main slide 22, as indicated at 45, and are connected by pins 46 with cam slide extensions 47. These extensions 75 are slidably mounted in slide-ways 42^a in the upper side of the portion 22^a, or main slide extension of the main slide 22. The pins 46 pass through reciprocation-permitting slots 46^a in the portion 22^a. In order 80 that the cam slides shall be moved together they are connected by a plate 48 attached to the slides at 49, the plate being slotted at 50 for passage of the shaft 24 to permit reciprocation with respect thereto. The 85 plate carries cam rollers 51 and 52, the roller 51, for cooperation with the upper cam, 28, to give forward, or right-hand, motion to the slides and the other, 52, for cooperation with the lower cam, 29, to give backward, or left-hand motion. 90

The contours, and relative motions, of the cams 10 for the ejectors, the cam 23 for the slide 22, and the cams 28—29 for the cam slides, and the reciprocations of the 95 plungers, may be timed as desired for proper operation, and I prefer a timing substantially such as that graphically represented in the chart comprising Fig. 7.

I will now briefly describe this chart, and 100 then will briefly review the operation of the press as thus far described, with incidental reference to the chart.

In the chart are shown four curves. "I" indicates the positions of the main slide, 105 "II" the positions of the cam slides, "III" the positions of the ejectors, and "IV" the positions of the plungers. In curves I and II the lowest portions of the curves represent the initial, or left-hand position of the slides, and distances above those portions represent the distances of the slides away from initial position. In curve III the lowest portion represents the lowest position of the ejectors, and distances above the 110 distances above the lowered position. In curve IV the rise and fall of the curve represents the rise and fall of the plungers. Distances along the horizontal axis indicate 115 degrees of rotation, all the cams and the crank for the plungers rotating in the ratio 1:1. Where curves I and II are parallel, the main slide and the cam slides are moving at the same speed (or standing) together and the couplings are stationary in 120 the main slide. The extreme ends of the curve represent the positions shown in the structure figures of drawings, that is, with the slides at the extreme right and punching occurring. 125

In operation:—At the beginning of a cycle (a) the various slides are at the extreme left in initial position and the initial dwell beginning. Drawing has previously occurred and the plungers are rising and so are the ejectors. Now the cam-slides move forward (a—b) permitting the couplings to move into coupling position. About at this time the partially drawn shells and the scrap 10 are stripped from the rising plungers and drop between the coupling units (the units not advancing to such a position as to prevent this) and the extreme left-hand couplings encompass the new cup standing below the bottom of the feed pipe, they not advancing sufficiently to prevent a cup dropping between them, should the cup be feeding from the pipe. While the initial dwell of the main slide is still continuing (a—d) 15 the ejectors completely rise and remain up (e—e) during some of the time in which the main slide is moving to the left (d—f) and drawing along the new cup and the partially drawn shells to their new positions. 20 (It will be noted from the parallel curves that the cam slides and main slide move forward together keeping the couplings in coupling position.) The ejectors are of such length and diameter that, when up, they 25 substantially fill the holes in the dies and lie flush with the tops of the dies thus to present a smooth "floor" for the shells to slide over as they are drawn forward and are timed to be up and prevent catching of a shell in a die when the forward motion begins. 30 When the right hand dwell of the slides is reached (f) and, hence, the new cup has been placed over the first die, and each partially drawn shell over the next die to that in 35 which it has just been drawn (and the scrap has been moved from the last die to the air box) drawing may begin. It occurs during the dwell, since the plungers descend and rise at this time and draw approximately at 40 g say, the ejectors descending (e—h) to not interfere with the drawing. After the drawing, and during the right dwell (f—i) of the main slide, the cam slides are moved to the left (j—k) to move the couplings into 45 retracted position. Then all slides move back (i—a) to initial position (a) completing the cycle. Desirably the travel of the plungers is such that, when the main slide starts to move to the left the 50 shells are not free of the plungers, whereby the plungers hold the shells, and make doubly sure that they will not be carried back by the main slide should the cam slides not yet have caused the couplings to sufficiently retreat; in such a case the 55 couplings will slide past the shells, the shells compelling the retreat of the couplings. 60 In the described arrangement for coupling the articles to the main or carrying slide it is to be noted that the position and move-

ments of the couplings are determined by positive means—the cam slides—thus providing for accuracy and positiveness, and eliminating possibility of harm to the shells. These are results which could not be uniformly obtained were the shells relied upon to normally actuate the couplings.

It will be understood that the cams 28—29 are substantially complementary, the contours being such that the cam 29 and roller 52 do not interfere with the moving forward of the cam slides by the cam 28, nor the cam 28 and roller 51 interfere with the moving backward of the cam slides by the cam 29. It will be seen that this double-cam construction gives relatively simple cam surfaces and eliminates the use of a return spring, as compared to a single-cam construction. All the various cams may be contoured substantially as illustrated, indeed in the chart curves I, II and III are substantially cam developments.

Having described the drawing parts of the machine I will now explain those parts of the machine, designated generally as A^H , 90 for feeding the cups from the hopper H to the feed pipe 5, to be taken from adjacent the bottom thereof by the main slide or shifter and shifted to the first die. This mechanism feeds cups into the upper end 95 of the pipe in substantial correspondence with the taking of the cups one-by-one from the bottom of the pipe 5. Reference is made to Figures 8 to 11 more particularly.

In the side 53 of the hopper H , and practically forming the major portion of the side, is inserted a disc 54 mounted for rotation on the shaft 55 which latter is mounted at 56 in the hopper. This disc 54 in its rotation takes the cups from the hopper and introduces them one-by-one into the top of the feed pipe 5. It is driven by the gear wheel 57 rotatably mounted on the rear wall of the hopper at 58 and meshing with teeth 59 on the periphery of the disc. The gear 100 57 is driven from the shaft 60 (Fig. 1) for example by the crossed belt 61 and wheel 62 though a more complicated driving connection may be used if desired. This shaft 60 is the main drive shaft of the machine. 105 Not only is it belted, at 61, to the disc 54, but also (a) it carries the crank 63 for driving the plungers 3—(through the connecting rod 64) and (b) is geared, at 65, to the shaft 24 which carries the cams 110 23 and 28—29, and is geared at 66 to the ejector-driving shaft 11. Thus the feeding disc 54 performs its feeding rotations in 115 timed relation to the plungers, slides and ejectors.

Now to describe the detailed structure which enables the disc 54 to feed the cups to the pipe 5:—First, I shall describe the features which enable the disc to feed in its simple uninterrupted manner, substantially 120 125 130

omitting those features which, on occasion, introduce variations into the simple feeding thereby to prevent over-filling of the feed pipe; and, second, I shall take up the 5 structures which introduce variations into the feeding. Mounted in the side of the hopper is an annulus 67 closely surrounding the disc 54. Throughout the inner periphery of this annulus (except as in- 10 terrupted by the pipe 5) is a cup channel 68. This channel, for the longer span substantially between the line $x-x$ (Fig. 8) and the line $y-y$, i. e. through a large part 15 of its length, is widely open to the interior of the hopper as indicated at 69 in Fig. 9. Throughout the rest of its length the channel has but a narrow slot, as indicated at 70 in Fig. 9. This slot 69-70 is sufficiently wide at its part 69 to permit cups to fall 20 into or out of the slot, and at its part 70 is sufficiently narrow to prevent the cups falling out. The upper end of the pipe 5 is introduced tangentially into the annulus 67 at 71, its passage forming a continuation 25 of the channel 68.

A series of cup carriers, designated generally as 72, are carried near the periphery of the disc 54. A complete circumferential series is ordinarily used, but for simplicity 30 in the drawings many of the units of such series are omitted. Each carrier comprises a hook, pick-up member, or article-carrying projection, 73, whose hook-end 74 is, normally, located to travel along in the channel, facing in the direction of travel of the disc, i. e. anti-clockwise in Fig. 8. The hook is fast to a shank 75 which is rotatably mounted in the disk 54. At its outer end the shank 75 has a crank 76. On this crank 40 is mounted a cam roller 77, and also a trip-finger-and-actuator 78 stationary with respect to the crank, constituting a controller for the hook. A spring 79, attached to the disc 54 by the screw 80 and to the finger 45 (and crank) at 81, tends to turn the crank clockwise, thus to cause the hook to snap, or swing quickly, out of the channel, its end 74 withdrawing out of the channel backwards (with respect to the direction of 50 travel of the disc 54 and carrier 72 as a whole) to wholly withdraw from the channel and the slot 69-70. This tendency of the spring 79 is, normally, resisted by a ball-and-socket catch comprising a ball 82 55 permanently held in the disc 54 but urged into the socket 83, of the crank 76, by the spring 84.

The finger 78 is contoured to provide 60 along its edge a tripper projection 85, a pushing and lifting surface 86, and a lifting surface 87. The forward end of the finger which presents the surfaces 86 and 87 is offset outward (relative to the outer face of the disc 54), at 88, placing the surfaces 86 and 87 in a plane outward of the plane 65 of the tripper projection 85 and the here- 65 after mentioned trips 89 and 104 but in the plane of the pin 125 hereafter men- 70 tioned. The finger and hook are actuated by the trip, or projection, 89 located near the mouth of the pipe 5, and located in the plane of travel of the projection 85 and they are also actuated by the cam track 90 which contacts the roller 77 and has, it will be noted, a dip 91 near the tripping projec- 75 tion 89, and a subsequent rise 92. The projection 89 is carried upon a supported band and steadyng track 93, the cam track 90 and supporter band being carried by bridges 94 from the annulus 67 which lie 80 outward of, and in non-interfering position with respect to, the carriers. The projection 85 is located in a plane outward of the cam track 90 and the hereafter mentioned slides 100, 107, 108. 85

The hopper H has an inclined bottom, as indicated at 95, down which the cups slide toward the channel 68, the volume of cups having access to the channel being controlled by the gate 96, vertically adjustable, 90 by the bolt-and-turn-nut 97, on the partition wall 98, to determine the height of the opening 99 giving access to the channel 68.

In the normal, steady, uninterrupted-feed operation the action is as follows:— 95 Certain of the shells in the hopper descend by gravity into the channel 68 in its lower arc. Of these, some lie in the channel with their open ends facing the hooks which, depending into the channel 68 from the disc 54 and held in that position by the ball-and-socket latch 82-83, are moving forward (anti-clockwise) in the channel with their ends 74 facing forward along the channel. These cups are picked up on the hooks and carried along. The hooks prevent the cups from falling out of the open part 69 of the channel, and narrow part, 70, of the slot 69-70 is too narrow to permit dropping out of the cups (but of course 100 wide enough for entrance of the hook body). The hooks remain in this projecting-into-the-channel position until the tripper projection 89 near the entrance of pipe 5 is reached, there being nothing inserted 110 in the path of the finger 78 to move it from its normal tangential position. Upon reaching the projection 89 the projection 85 wipes it. The ball-and-socket latch 82-83 115 is overcome, and the hook is moved backward out of the channel in position to clear the pipe 5 (the dip 91 in the cam track 90 permitting this); and the cup passes into the pipe 5, open end up and ready to be introduced to the dies when it reaches the 120 bottom of the pipe. As the hook continues its travel the rise 92 in the cam track moves the finger back to tangential position, the

125

ball 82 snaps into the socket 83, and the hook is returned to the cup channel, ready to pick up another cup.

Next, I will describe the structures where-
5 by the feeding of the cups to the pipe 5 is interrupted on occasion, while the disc 54 continues to rotate. The purpose of this interruption is to insure that the pipe 5, or more exactly the portion of the channel 68
10 near the pipe, will not become filled with a column of cups so long as to interfere with easy and harmless moving of the cups along the channel, in case the disc 54 conveys more cups than are required by the drawing parts
15 of the machine; a column of cups substantially longer than that permitted by the present arrangement having been found inadvisable.

The supporting band 93 carries a slide
20 strip 100 which is attached to the band by the pin 101 passing through the inclined slot 102 in the slide strip. This slot is inclined to the longitudinal axis of the slide strip in such a direction, as shown, that when
25 the strip is slid clockwise its rear end 103 is shifted radially outward, and vice versa. Near its rear end the strip carries a projection, or trip, 104 which projects outward from the strip into the plane of the tripper
30 projections 85 on the fingers 78 which govern the cup hooks 73. When the strip is in its backward position, and the tripper 104 thus in its radially outward position, the trip lies out of the path of the tripper projections
35 85. With the trip in forward position, the projection 85 of each approaching finger strikes it, the ball-and-socket latch 82-83 is overcome, the spring 79 snaps the hook 73 backward out of the carried cup, and the
40 cup drops back into the hopper through the wide part 69 of the slot 69-70 in the channel 68; thus no cups are carried to the pipe 5. (It will be noted that the track 90 is interrupted at 105 to permit the swinging of the carrier 72 and then is resumed with a surface 106 to rock the carriers back into normal or tangential position.)

For controlling the shifting of the slide
45 100 and, hence, the position of the trip 104, the mechanism is as follows:—The slide 100 is one of a series of slides, the series comprising the slide 100 or trip slide, the slide 107 or connector slide, and the slide 108 or controller slide. The slides are held circumferentially slidable on the supporter band 93 by pin-and-slot connections 109. The slide 107 has the other slides hinged to its opposite ends at 110 and 111, the hinges giving to the slide 100 the freedom necessary
55 for the radial travel of the trip 104, and giving a freedom of swing to the slide 108 for a purpose presently to appear. The series of slides are urged to backward, or trip-104-out-of-the-way, position by a spring 112 connected to the casting or annulus 67 at 113

and to the slide 107 at 114. A stop 115, for holding the slides in forward position against the pull of the spring 112, is pivoted on a pin 116 fixed to the side of the hopper. It fits behind a rearwardly facing shoulder 70 117 on the slide 107 and is urged toward the slide by the spring 118 having one end fixed, as to the pin 116, and its other end pressing on the hereafter named block 122. For lifting the stop 115 there is provided a lifter 75 lever 119 which is fast connected with the stop 115, by the holding blocks 121 and 122 for the stop and lever respectively being clamped to the sleeve 123 rotatable on the stud 116. Evidently the parts 115, 119 etc. 80 constitute a species of latch. The lever 119 has its end 124 lying in the plane of the projections 85 on the fingers 78 and behind the plane of the ends 87 of the fingers. Upon the forward end of the slide 108 is 85 a puller pin 125, projecting into the plane of the off-set ends 87 of the fingers 78 but radially beyond the path of travel of the projections 85, and ends 87 on fingers 78 when the slide 108 is in radially inward position and the fingers in tangential position. 90

Behind the puller pin is a triangular slot 126 in the slide 108, which encompasses a guide pin 127 on the supporting band 93 and provides by its length 126^a for the required longitudinal movement of the slide 108, and by its height 126^b for the required swing about the hinge 111. 95

The operation of the above mechanism is as follows:—

In normal unrestricted operation the slides 100, 107, and 108 are pulled to the right by the spring 112, with the stop 115 riding on the outer edge of the slide 107 just ahead of the shoulder 117, the forward end of the slide 108 lying in lowered or radially-inward position, and the trip 104 resting in radially outward position. With the parts so placed the fingers 78 remain in tangential position and the hooks in radial or cup-carrying position 100 until the stop 89 is reached; and the cups are uninterruptedly fed to the pipe 5. Now, should the pipe 5 fill up, by reason of the disc 54 feeding faster than is required, and the column of cups reach back along the arc of the channel 68, the top of the column will ultimately reach a point (say X) somewhat in rear (circumferentially) of the puller pin 125 on the forward end of the puller slide 108. When a hook reaches the head of this column the resistance encountered overcomes the ball-and-socket 82-83, which holds the cup carrier in normal position with the finger 78 in tangential position, and the spring 79 snaps the carrier into abnormal position with its hook free of the slot and its finger in radial position (see upper left hand showing in Fig. 8), the dip 91 in the cam track 90 permitting this. With the finger in radial position, when it reaches 115 120 125 130

the pin 125 it pushes on the pin with the edge 86 and pulls the three slides forward. The pin rides up the edge 86 to ultimately let the finger pass under the pin, and the stop 5 115 drops behind the shoulder 117 to lock the slides in forward position. This movement of the slides pulls 104 into the path of the projections 85 on the fingers so as to trip the cup carriers. Henceforward the hooks are 10 freed from the cups and no cups are carried forward to the arc of the cup channel 68 above the pipe 5. As the cups continue to be discharged from the pipe 5, the time eventually arrives when the length of the column 15 of cups behind end 124 of the lifter lever 119 is so short that a finger 78 is not turned soon enough to swing the projection 85 of the finger 78 out of the way of the end 124. So the projection 85 strikes the end 124, lifting 20 the lever 119 and so lifting the stop 115 from behind the shoulder 117, the spring 112 pulls the slides back to normal position, and the trip 104 is moved out of the path of the projections 85. The cup carriers 72 no longer 25 are tripped, and the regular, interrupted cup feeding is resumed.

Should it occur that, with the strip 108 in lowered position, the top of the column of cups lies so close to the pin 125 that, when 30 the carrier snaps back, the finger strikes the pin on its forward side, the curved surface 87 will merely wipe on the forward side of the pin, lifting the strip 108 if necessary, the contour and location of the slot 126 permitting this.

As to certain of the less important details:—

Desirably a cup spring 128 is mounted on the casting 67 and has its triangular end 40 projecting partially across the channel 68 through a slot 129 in the outer periphery of the channel, for removing any cups that are not carried on a hook but may be pushed along the channel ahead of a hook-carried 45 cup.

For inspection purposes the annulus 67 may be slotted on its outer periphery, as at 49 (Fig. 1), through such length as desired, such slot of course being narrower 50 than the cups. The main slide 22 may be held on the machine bed by guides 131. The plungers may be of the general character indicated in Figure 1. The ends of the coupling units may have increasing heights to 55 correspond with the increasing heights of the shells as indicated at 25^b; the ends of the units of the first pair may be bevelled back as indicated at 25^c in Fig. 5, instead of being substantially perpendicular like the other 60 units, thus to permit the end of the pipe 5 being brought close to the units to discharge the cups therebetween; the last pair of couplings, or scrap couplings, may desirably have their ends bevelled back as indicated at 25^d

(Figs. 3 and 4) and be of considerable height 65 to insure their receiving the ring of scrap as it is stripped from the plunger, and their presenting a proper passage for the air from the pipe 21, and the right hand (Fig. 3) sides of the recesses 25^a of the last pair may 70 be undercut as indicated by the dotted lines at 132, for clearance of any scrap upon the return of the slides. As will be understood, the heights of the various fingers are such, and the timing such, that there is no interference with the movements of the fingers 75 and slides by the plungers.

I claim:—

1. In a drawing press, in combination, a single hopper, and a pair of pressing units; 80 each such unit including a feed conduit individually connected to said hopper, elements to draw the articles fed by the conduit, means to convey the articles from the conduit to said elements and shift them relative to the elements, means, separate and distinct from the corresponding means of the other unit, to feed the articles from the hopper to the conduit, and means for driving certain of said drawing elements, said 90 conveying and shifting means, and said feeding means in unison.

2. In a drawing press for drawing previously prepared individual articles, in combination, devices for operating upon 95 the articles and including a drawing die, and a receptacle for the miscellaneous and simultaneous reception of a plurality of the articles to be operated upon, said machine 100 providing a plurality of locations for articles in proximity to said devices and said devices and receptacle being associated for travel of the articles from a position adjacent the receptacle to one of said locations, driven means for arranging the articles in 105 proper attitude to be operated upon by said drawing die and, for conveying the articles in said attitude one-by-one from said receptacle to said position for travel to said associated location and to said die, driven means 110 for moving the articles one-by-one from such location to another, and driving means for driving said two driven means in timed relation each to the other.

3. In a drawing press for drawing previously prepared individual articles, in combination, a receptacle for the miscellaneous and simultaneous reception of a plurality of the articles to be drawn, drawing elements including a drawing die, a feed conduit in proximity to said receptacle and located to discharge the articles to a position adjacent 120 said die, driven means for taking the articles one-by-one from such position and shifting them toward said die, driven means for taking the articles one-by-one from said receptacle; arranging the articles in proper attitude to be operated upon by said draw-

ing die, and delivering them in said attitude to said conduit, and means for driving said two driven means.

4. In a drawing press for drawing previously prepared individual articles, in combination, a receptacle for the miscellaneous and simultaneous reception of a plurality of the articles to be drawn, drawing elements including a drawing die, a feed conduit, in 10 proximity to said receptacle and located to discharge the articles to a position adjacent said die, driven means for taking the articles one-by-one from such position and shifting them toward said die; such means including an article-handling device movable into and out of handling position and driven mechanism for positively controlling the movements of said device; driven means for taking the articles one-by-one from said 20 receptacle; arranging the articles in proper attitude to be operated upon by said drawing die, and delivering them in said attitude to said conduit, and means for driving said two driven means and said driven mechanism.

5. In a drawing press for drawing previously prepared individual articles, in combination, a receptacle for the miscellaneous and simultaneous reception of a 30 plurality of the articles to be drawn, drawing elements for operating in succession upon each of said articles and including a bank of dies, a feed conduit in proximity to said receptacle and located to discharge articles to a position adjacent the first die of said bank, driven means for taking the articles one-by-one from such position and shifting each from die to die, driven means for taking the articles one-by-one from said 40 receptacle, arranging the articles in proper attitude to be operated upon by said drawing die, and delivering them in said attitude to said conduit, and means for driving said two driven means.

45 6. In a machine of the character indicated for operating upon articles and presenting a plurality of longitudinally spaced locations for the articles; mechanism for moving the articles from one location to another, and comprising, in combination, a driven shifter in proximity to said locations, and carrying a mechanically controllable coupling device for coupling an article to, and uncoupling it from, the shifter, said shifter being mounted for a movement in the direction of the spacing of said locations, and corresponding to said spacing, to move the coupling device from correspondence with one location to correspondence with another, 50 positively driven mechanical means, as distinguished from the article operated on, and mechanically differentiated from the shifter, for controlling the activities of said device in its movements to and from coupling position, and driving means for driving said 55 60 65

shifter and said controlling means in timed relation each with the other.

7. In a machine of the character indicated for operating upon articles and presenting a plurality of longitudinally spaced locations 70 for the articles; mechanism for moving the articles from one location to another and comprising, in combination, a driven shifter in proximity to said locations, and carrying coupling-device means for coupling an article to, and uncoupling it from, the shifter, the number of said means being at least equal to the number of said locations, said shifter being mounted for a movement in the direction of the spacing of said locations, 80 and corresponding to said spacing, to move the coupling-device means from correspondence with one location to correspondence with another, and driving means for said shifter. 85

8. In a machine of the character indicated for operating upon articles and presenting a plurality of longitudinally spaced locations for the articles; mechanism for moving the articles from one location to another, and comprising, in combination, a driven 90 shifter in proximity to said locations and carrying a mechanically controllable coupling device for coupling an article to, and uncoupling it from, the shifter, and adapted to occupy a coupling or an uncoupling 95 position, said shifter being mounted for a movement in the direction of the spacing of said locations, and corresponding to said spacing, to move the coupling device from correspondence with one location to correspondence with another, means for moving said device toward one of said positions, positively driven mechanical means, as distinguished from the article operated on, and mechanically differentiated from the shifter, 100 for moving said device toward its other position, and driving means for driving said shifter and said driven means in timed relation each with the other. 105

9. In a machine of the character indicated for operating upon articles and presenting a plurality of longitudinally spaced locations for the articles; mechanism for moving the articles from one location to another, and comprising, in combination, a driven 110 shifter in proximity to said locations and carrying a mechanically controllable coupling device for coupling an article to, and uncoupling it from, the shifter, and adapted to occupy a coupling or an uncoupling position, said shifter being mounted for a movement in the direction of the spacing of said locations, and corresponding to said spacing, to move the coupling device from correspondence with one location to correspondence with another, means for moving said device toward one of said positions, positively driven mechanical means, as distinguished from the article operated on, and mechanically differentiated from the shifter, 115 120 125 130

for moving said device toward its other position, one of said means being located substantially directly in alignment with, and of substantially no greater width in the direction of the spacing of said locations than, said coupling device, and driving means for driving said shifter and said driven means in timed relation each with the other.

10. In a machine of the character indicated for operating upon articles and presenting a plurality of longitudinally spaced locations for the articles; mechanism for moving the articles from one location to another and comprising, in combination, a driven shifter in proximity to said locations and carrying a mechanically controllable coupling device for coupling an article to, and uncoupling it from, the shifter, said shifter being mounted for a movement in the direction of the spacing of said locations, and corresponding to said spacing, to move the coupling device from correspondence with one location to correspondence with another, means for moving said device into coupling position, positively driven mechanical means, as distinguished from the article operated on, and mechanically differentiated from the shifter, for moving the device from coupling position, and driving means for driving said shifter and said driven means in timed relation each to the other.

11. In a machine of the character indicated for operating upon articles and presenting a bed and a plurality of longitudinally spaced locations thereon for the articles; mechanism for moving the articles from one location to another and comprising, in combination, a driven carrier slide, carried upon said bed in proximity to said locations and carrying a controllable coupling device for coupling an article to, and uncoupling an article from, the carrier slide and including a coupling unit shiftably mounted with respect to said slide for movement toward and from said locations to occupy a coupling or an uncoupling position; said carrier slide being mounted for a movement in the direction of the spacing of said locations and corresponding to said spacing, and said unit being provided with a cam-surface-following structure; means for moving said coupling device, including the coupling unit thereof, toward one of said positions, driven means for moving said device toward its other position and including a cam slide slidable with respect to said cam-surface-following structure and having a cam surface for cooperation with said structure and contoured to shift said unit during relative movement, and driving means for driving said carrier slide and said driven means in timed relation each with the other.

12. In a machine of the character indicated for operating upon articles and pre-

senting a bed and a plurality of longitudinally spaced locations thereon for the articles; mechanism for moving the articles from one location to another and comprising, in combination, a driven longitudinally apertured carrier slide carried upon said bed and located to place its aperture in register with said locations as the slide is longitudinally shifted and carrying a pair of opposed coupling units located one at each side of said aperture and shiftable toward and from said aperture to occupy a coupling or an uncoupling position, for coupling an article to, or uncoupling an article from, the carrier slide, said carrier slide being mounted for a movement in the direction of the spacing of said locations and corresponding to said spacing, and each said unit being provided with a cam-surface-following structure, means for moving said units toward one of their positions, driven means for moving said units toward their other position, such means comprising a pair of cam slides arranged one at each side of said aperture and each slidable with respect to its co-related cam-following structure and contoured to shift its co-related unit during relative movement, said cam slides being mated to each shift its co-related unit in a direction opposite to that in which the opposed unit is shifted, and driving means for driving said carrier slide and said driven means in timed relation each with the other.

13. In a machine of the character indicated for operating upon articles and including devices for operating on the articles and a receptacle for the articles to be operated upon, said devices and receptacle being associated for travel of the articles from a position adjacent the receptacle to the devices; mechanism for taking the articles from said receptacle and placing them in said position, said mechanism comprising, in combination, a driven member, a trippable article carrier carried with said member to travel therewith, normally located in article-carried position, and trippable into article-free position, said member being located with respect to said receptacle to give access of said carrier to said receptacle and to said adjacent position during driving of said member, a tripping device located in the path of said carrier adjacent such position, and means for driving said driven member.

14. In a machine of the character indicated for operating upon articles and including devices for operating on the articles and a receptacle for the articles to be operated upon, said devices and receptacle being associated for travel of the articles from a position adjacent the receptacle to the devices; mechanism for taking the articles from said receptacle and placing them in said position, said mechanism comprising, in combination,

5 a driven member, a trippable article carrier carried with said member to travel therewith, normally located in article-carried position, and trippable into article-freed position, said member being located with respect to said receptacle to give access of said carrier to said receptacle and to said adjacent position during driving of said member, a major tripping device located in the 10 path of said carrier adjacent such position, an auxiliary tripping device located ahead of said major device along the path of travel of said carrier, and removed from such position, and shiftable into and out of said 15 path, means for shifting said auxiliary device into and out of said path and operable by said carrier on occasion, and means for driving said driven member.

15. In an article feeding structure, in combination, an article receptacle having a wall presenting a substantially circular aperture and surrounding annular article channel, said channel having a longitudinal opening therein facing said aperture and also having 20 an article exit, a rotatable feeding disc located at said aperture and concentrically positioned with respect to said channel with its periphery in close proximity to said channel, an article carrier movably mounted on 25 said disc adjacent its periphery for movement into and out of carrying position and comprising an article-carrying element and a controller, said carrying element lying in article-carried position with relation to said 30 channel when said carrier is in normal position and lying in article-freed relation when in abnormal position, means for holding said carrier in normal position, a trip device arranged adjacent said exit for cooperation 35 with said controller to move said carrier toward abnormal position, means for returning the carrier to normal position, and means for driving said disc.

16. In an article feeding structure, in combination, an article receptacle having a wall presenting a substantially circular aperture and surrounding annular article channel, said channel having a longitudinal opening therein facing said aperture and 40 also having an article exit, a rotatable feeding disc located at said aperture, and concentrically positioned with respect to said channel with its periphery in close proximity to said channel, an article carrier movably mounted on said disc adjacent its periphery for movement into and out of carrying position and comprising an article-carrying element and a controller; said controller comprising a shank pivoted in said 45 disc and carrying said element, and a tripper finger and related cam roller carried by said shank; said carrying element lying in article-carried position with relation to said channel when said carrier is in normal position and lying in article-freed relation when

5 in abnormal position, means for holding said carrier in normal position, a trip device arranged adjacent said exit for co-operation with said tripper finger to move said carrier to abnormal position, a cam track adjacent 70 said disc and located for travel of said roller thereupon, said track having a portion compelling the return of said carrier to normal position, and means for driving said disc.

17. In an article feeding structure, in combination, structure providing an article channel, said channel having an exit therefrom and having a longitudinal opening therealong, a portion of said opening removed from said exit having sufficient width 80 to permit articles to escape from said channel, a receptacle for articles adjacent said channel, and driven means for taking articles from said receptacle and carrying them along said channel to said exit, such means 85 including a driven member and a trippable article carrier carried thereby, said carrier having an article-carrying element travelling in said channel, also having a controller and also having connections between said element and controller for moving said controller into carrier-tripped position under pressure upon said element, a trip located adjacent said portion of said longitudinal opening and shiftable into and out of the 90 path of said controller, devices for causing shifting of said trip into said path and means for causing shifting of it out of said path, said devices including an element movable to bring about shifting and lying in the path of said controller when the carrier is in tripped position, to be moved thereby; whereby when said articles fail to discharge through said exit, and said carrying element strikes one, and the carrier is thereby moved to tripped position, said controller moves said movable element, and said devices move said trip into carrier-tripping 95 position.

18. In an article feeding structure, in combination, a receptacle, structure providing a channel for the articles, with said channel located to receive articles from the receptacle and having an exit and also having an open portion removed from said exit 110 for the discharge of articles on occasion, said portion being located ahead of said exit relative to the travel of the hereafter named carrier, a travelling carrier for carrying articles along said channel from said receptacle and trippable to discharge articles, both by a trip and by pressure of portions of said carrier against the articles, a shiftable trip for said carrier adjacent said open portion and shiftable into tripping position, means for shifting said trip into carrier-tripping position when said carrier is tripped by its pressure upon said articles, and means for moving said carrier.

19. In an article feeding structure, in com-

- 5 bination, a receptacle, structure providing a channel for the articles, with said channel located to receive articles from the receptacle and having an exit and also having an 5 open portion removed from said exit for the discharge of articles on occasion, said portion being located ahead of said exit relative to the travel of the hereafter named carrier, a travelling carrier for carrying articles along said channel from said receptacle, trippable to discharge articles, both by a trip and by pressure of portions of said carrier against the articles, and having a pusher for cooperation with the hereafter named pusher-cooperating element when said carrier is 10 in tripped position, a shiftable trip for said carrier adjacent said open portion and shiftable into and out of tripping position, operative connections extending from said trip to a location between said trip and said exit and having a pusher-cooperating element for cooperation with said pusher, whereby said trip shifts, and means for driving said carrier.
- 15 20. In an article feeding structure, in combination, a receptacle, structure providing a channel for the articles with said channel located to receive articles from the receptacle and having an exit and also having an 20 open portion removed from said exit for the discharge of articles on occasion, said portion being located ahead of said exit relative to the travel of the hereafter named carrier, a travelling carrier for carrying articles along said channel from said receptacle, trippable to discharge articles, both by a trip and by pressure of portions of said carrier against the articles, and having a pusher for cooperation with the hereafter named pusher-cooperating element when said carrier is 25 in tripped position and a latch lifter for contact with the hereafter named latch when the carrier is in untripped position, a shiftable trip for said carrier adjacent said open portion and shiftable into and out of tripping position, operative connections extending from said trip to a location between said trip and said exit and having a pusher-cooperating element, for cooperation with said carrier to move said trip into trip-active position, a latch for holding said connections in trip-active position, means releasable by said latch to move said trip to trip-inactive position, and means for driving said carrier.
- 30 21. In a machine of the character indicated and for operating upon articles, in combination, receptacle for the articles to be operated on, devices for operating on the articles, and means for feeding articles from said receptacle to said devices; such means comprising a member having an article channel in communication with said receptacle and provided with an article exit associated with said devices, means for moving articles along said channel to said exit and comprising a driven member and a carrier carried by said member; such carrier comprising a projection to travel in said channel, a shank rotatable in said member and carrying said projection, and a controller mounted on said shank; means for causing turning of said carrier with said shank, means to prevent such movement on occasion, a trip for said controller to overcome said preventing means on occasion, a second means to turn said carrier and adverse to said first named turning means, and means for driving said driven member.
- 35 22. In a machine of the character indicated and for operating upon articles, in combination, a receptacle for the articles to be operated on, devices for operating on the articles, means for feeding articles from the receptacle to said devices and comprising a driven member in proximity to said receptacle and carrying an article carrier located in communication with said receptacle to take articles therefrom, such carrier being trippable from article-carried position to article-freed position and having a pusher portion and a trip-contacting portion, a shiftable trip and means for operating the same; such operating means comprising a trip-carrying slide, and a connected puller slide carrying an element in the path of said pusher portion when said carrier is in one of its positions, whereby when said carrier is in such position said carrier in its travel slides said slides and shifts said trip; and means for driving said member.
- 40 23. In a machine of the character indicated and for operating upon articles, in combination, a receptacle for the articles to be operated on, devices for operating on the articles, means for feeding articles from the receptacle to said devices and comprising a driven member in proximity to said receptacle and carrying an article carrier located in communication with said receptacle to take articles therefrom, such carrier being trippable from article-carried position to article-freed position and having a latch-releasing portion, a shiftable trip and means for operating the same; such operating means comprising a latch-held slide connected to said trip to move the same, and means for moving said slide when released from said latch; a latch having an element in the path of said latch-releasing portion when said carrier is in one of its positions, whereby when said carrier is in such position said carrier in its travel releases said latch and said slide-operating means moves said latch-held slide and shifts said trip, and means for driving said member.
- 45 24. In a shell drawing press for drawing open-ended cups into shells, in combination, a die bed provided with a longitudinal series of dies and presenting an article rest
- 50 55 60 65 70 75 80 85 90 95 100 105 110 115 120 125 130

at one end of said series and a scrap escape at the other, a plunger holder reciprocatable to and from said bed and carrying a series of plungers for cooperation with said dies, 5 an article hopper located above said bed and presenting a vertically-lying annular article channel slotted along its inner periphery, the slot being wide, article-receiving, and article-releasing along its lower portion and 10 a part of its upper portion, and narrow and article-retaining along another part of its upper portion, a feed conduit extending tangentially from said channel adjacent the narrow portion of said slot to discharging 15 position at said rest, a feed disc rotatably mounted closely adjacent said channel and concentric therewith, a series of trippable cup carriers mounted with the said disc adjacent its periphery and trippable by trips 20 and also under pressure of the hereafter named holder on cups, and each provided with a cup holder and a controller, said cup holder being arranged to project into said channel and carry cups when the carrier is in untripped position and to discharge cups when the carrier is in tripped position, a trip for tripping the carriers adjacent the entrance to said conduit, an auxiliary trip for the carrier arranged ahead 25 30 of the wide upper portion of said slot, and shiftable into and out of tripping position, operative connections extending from said auxiliary trip to adjacent the entrance to said conduit and operable by a tripped car- rier to move said trip into active position, 35 and operable by an untripped carrier to move the trip into inactive position, and means for returning the carriers to untripped position; a driven carrier slide reciprocatable on said bed longitudinally of said 40 series of dies and carrying a series of article-coupling pairs spaced in correspondence with the spacing of said article rest, the dies, and the scrap escape, means for moving the units of said pairs to coupling position, a 45 driven device for controlling the positions of said units, i. e. coupled or uncoupled, and reciprocatable relatively to said carrier slide, a series of driven ejectors for lifting the partially drawn shells from the 50 dies into position to be coupled to the carrier slide by the coupling units, and timed means for driving the carrier slide and controlling device in timed relation to provide for coupling the cup at the rest, the 55 partially drawn shells, and the scrap, to the carrier for forward movement therewith, and their subsequent release when new positions for them have been reached; and driving means to drive said plungers, to 60 drive said feed disc in a direction to carry the article carriers from said auxiliary trip to the entrance to said conduit, to drive said ejectors, and to drive said timed means, in 65 timed relation each with the other.

In testimony whereof I affix my signature.

WALTER S. ROTHERHAM.
